UNITED STATES PATENT OFFICE.

CHARLES B. JACOBS, OF WILMINGTON, DELAWARE, ASSIGNOR TO E. I. DU PONT DE NEMOURS & COMPANY, OF WILMINGTON, DELAWARE, A CORPORATION OF DELAWARE.

PROCESS FOR THE PRODUCTION OF COMPOUNDS BY GAS REACTIONS AND APPARATUS THEREFOR.

1,376,207.

Specification of Letters Patent. Patented Apr. 26, 1921.

Application filed September 27, 1919. Serial No. 326,763.

To all whom it may concern:

Be it known that I, CHARLES B. JACOBS, a citizen of the United States, and a resident of Wilmington, in the county of New Castle and State of Delaware, have invented a certain new and useful Process for the Production of Compounds by Gas Reactions and Apparatus Therefor, of which the following is a specification.

10 This invention relates to a process for the production of compounds by gas reactions, and apparatus therefor. More particularly, it relates to a process of, and apparatus for, producing compounds by electrolysis, and, 15 since, it finds application in the fixation of nitrogen, I describe it with particular reference to the production of nitrogen compounds. But, it will be understood that I do not restrict the invention to that particular art.

On account of the extreme chemical inactivity of free or elemental nitrogen, it has, heretofore, not been possible to make it combine directly in any material quantity 25 with either oxygen or hydrogen, except by the action of the electric arc or the electric discharge, in the case of oxygen; or the influence of a catalytic agent, in the case of hydrogen. Examples of these methods are, 30 the formation of oxids of nitrogen by the Birkeland-Eyde, Pauling, and similar arc processes, and the formation of ammonia by the Haber process. But the commercial operation of the arc process is confined to 35 localities where cheap power in large quantities is available, since its power efficiency is low, requiring from 6.5 to 8 kilowatt hours for the production of one pound of nitric acid or its equivalent. And the Haber process, for the direct union of nitrogen and 40 hydrogen to form ammonia, while very efficient from the standpoint of power consumed, has up to the present time been of commercial benefit only to those trained and 45 instructed by its originators. I have devised an electrolytic process, and an apparatus for the performance thereof, whereby nitrogen can be fixed in sufficient quantity, and with sufficiently high current effi-

ciency, to make the production of nitrogen 50 compounds, by this process, of commercial significance, and by the use of which various of the difficulties of previous processes are avoided.

One object of the invention is to provide 55 a process for the production of compounds by gas reactions.

Another object is to provide a process for the electrolytic production of nitrogen 60 compounds.

Another object is to provide a process for the electrolytic production of oxids of nitrogen.

Another object is to provide a process for the fixation of nitrogen in which an aqueous 65 solution of an electrolyte is electrolyzed and nitrogen, introduced into the solution, oxidized in such quantities and with such current efficiency as to make the process of commercial significance. 70

Another object is to provide apparatus suitable for use in, and for aid in, the performance of processes embodying the invention.

To these ends, and also to improve generally upon processes and apparatus of the character indicated, my invention consists in the following matters hereinafter described and claimed.

Without restricting my invention there- 80 to, I show in the accompanying drawings, and describe, an apparatus embodying the invention and for use in, and for aid in, the performance of processes embodying the invention. In the drawings:— 85

Figure 1 is a vertical, diametrical, section of a cell, substantially on line 1—1 of Fig. 2;

Fig. 2 is a horizontal section substantially on line 2—2 of Fig. 1, of the cell illustrated in Fig. 1, and 90

Fig. 3 is a conventional, diagrammatic, elevational, assembly view of an apparatus for the fixation of nitrogen and including a cell of the type illustrated in Figs. 1 and 2.

I have discovered that if a body of free 95 or elemental nitrogen be finely divided, as into fine streams, and the divisions brought into intimate physical contact with active

electrolytic oxygen and hydrogen at the moment of their liberation, combination between the nitrogen and those gases takes place in sufficient quantity to make the 5 production of nitrogen compounds, by a process based on the discovery, of commercial significance. In utilizing this discovery I prefer to make use of porous electrodes for the electrolysis and to force the 10 nitrogen through the pores of the electrodes.

With such a procedure, the great number 15 of small pores in the porous anodes and cathodes serves to break up the introduced body of nitrogen passing through the pores into such a fine state of division as to approach the ideal condition of having the nitrogen in solution in the electrolyte. With the body in this finely divided state, the 20 nitrogen comes into very intimate contact with the active electrolytic oxygen, or hydrogen, at the moment of their liberation on and within the anode, or cathode, and is in a condition to yield readily to oxidation and 25 hydrogenation in the electrolytic cell. The greater the porosity and the smaller the individual pores of the anode and cathode structures, the more nearly is the body of nitrogen subdivided into a state approaching 30 a condition which, for the purpose, amounts to having the nitrogen in actual solution in the electrolyte.

It will be seen that each stream of nitrogen as it passes along a pore is surrounded 35 by oxygen, or hydrogen, and thus an enormous extent of contact between the nitrogen and the oxygen and hydrogen is arrived at. The fineness of the porous structure of the anodes and cathodes which may 40 be used is limited only by that degree of fineness which would cause the passage of the nitrogen through the structure to force the solution out of the pores and thus stop electrolysis, and, consequently, the liberation 45 of oxygen and hydrogen on the active surfaces of the anode and cathode.

Various compositions for the porous anodes and cathodes, having the desired porosity and electrical conductivity and retaining 50 these properties by virtue of their resistance to chemical action within a cell, may be used. For anode construction for use in acid anolytes, I have found porous graphitized petroleum coke to give the best results. 55 In alkaline anolytes, such as sodium hydroxid solutions, fine steel wool, rammed into position in the electrode compartments, gives excellent results for both anodes and cathodes. For a wide variety of work, with 60 electrolytes of varying composition, I have used satisfactorily graphitized petroleum coke for the construction of both anodes and cathodes.

I shall now describe the illustrated cell, 65 explain briefly one way of carrying on the

process with the aid of the cell, and then note certain other matters, including results of certain of my experiments, as a further aid to the understanding of my invention. Referring now to the drawings:—

70

The cell, which is desirably cylindrical in form, comprises the outer container 1, desirably of glass, and the inner porous cup 2, say of unglazed earthen ware. The relative dimensions are such as to provide the 75 annular space 3, the space shown having substantially one and one-half times the capacity of the cup 2. The cup 2, or cathode compartment, and the space 3, of the container 1, or anode compartment, are each 80 partially filled with graphitized petroleum coke, as 4 or 5, to give porous electrodes, each composed either of a large porous single piece as is preferable, or, if desired, of a large number of packed small porous 85 pieces. Graphite rods as 6, 6, 6, with suitable electrical connections as 7, for each, are inserted in the anode compartment for carrying the current to the coke 5. Similarly, a graphite member 8, having suitable electrical connections 9, is inserted in the coke 4. 90

The member 8 serves also as a means for introducing nitrogen to the cathode, being in the character of a tube having, as shown, a passage 10 extending axially therein. The 95 member extends to the bottom of the coke 4 and is perforated as at 11 to provide for the passage of the nitrogen, thereby to introduce the nitrogen at the bottom of the cathode. Conveniently the member is enlarged, at its lower end, into a box form as indicated at 12.

A tube 13, of any suitable material, as 100 glass, and extending to the bottom of the coke 5 and around the annulus 3 in ring form, as indicated at 13^a serves for the introduction of nitrogen to the bottom of the anode. As shown, the tube is perforated along the ring 13^a, as at 14, for the passage 105 of the nitrogen.

A tube 15, also desirably of glass, and extending into the anode compartment to a position above the level of the solution 16, serves for the conducting away of the gases, as NO, produced by the anodic reactions; 110 likewise, a tube 17, say of glass, extending into the cathode compartment to a position above the level of the solution 16, serves for the conducting away of the NH₃.

Perforated partitions, as the rubber disk 115 18 and the rubber ring 19, are inserted in the compartments 2 and 1 to hold the coke in position, the spaces above the partitions serving as gas chambers 20 and 21. To close the cathode compartment and hold the 120 various rods and so forth in position, a stopper 22, desirably of rubber, is inserted in the upper end of the compartment 2, and seals 23 and 24, desirably of plaster of Paris, are applied to the compartments. If de- 125 130

sired, thermometers 25 and 26 may be provided.

The cell may be operated and the process carried out in the following manner, the process when carried out in such manner being of the "Class C" type mentioned later in the giving of experimental data:—The anode and cathode compartments of the cell are filled to a suitable level with the 5 electrolytic solution which may be an aqueous solution of an electrolyte, say nitric acid, sodium nitrate, sodium hydroxid, etc., containing the electrolyte in sufficient quantity, say 5 to 20%, to give a proper conductivity to the solution. Operating desirably at about 19° C., nitrogen is forced through the porous electrodes, from the bottom. The current is so regulated that the oxygen liberated on and within the porous structure 10 of the anode is, for practical purposes, sufficient to oxidize the introduced nitrogen only to NO.

The amount of nitric oxid formed at the anode is dependent on current regulation in 25 relation to the amount of nitrogen introduced. Also, the progress of the oxidation is affected by the anodic current density. As will be understood by those familiar with the art, these can be varied at will, to obtain 30 the desired conditions in each particular case. With the illustrated cell I have found an anodic current density of .04 to .05 ampere per square inch of superficial area of the anode satisfactory.

The nitrogen forced through the cathode combines only as NH₃ and the current regulation at the cathode is not of such importance as the regulation at the anode. Ammonia forms within the cathode compartment until the catholyte is saturated with ammonia whereupon ammonia gas is evolved through the outlet 17.

The evolved gases are passed into suitable absorbing systems, as will be understood, 45 the apparatus being say as conventionally outlined in Fig. 3; there, the source of supply of nitrogen under pressure is indicated by the tank N; the ammonia gas is absorbed in water from W in an ammonia absorption column A; the NO gas is passed first to the oxidation chamber O, air being introduced at a, and the NO₂ passes to the absorption column H' and to the absorption column H², water being supplied at W' for the formation of HNO₃, the dilute acid being transferred from H² to H' by acid egg E.

As described above, the process is, so far as practicable, so carried out that in the cell the nitrogen is oxidized only to NO, the further oxidation to HNO₃ taking place outside of the cell and, so, not at the expense of the oxygen being liberated by the cell. Thus, the most efficient condition is approached. That condition is, of course, that only one 60 molecular equivalent of oxygen is required 65

from the cell for one molecular equivalent of nitrogen oxidized, the cell acting merely as a nitric oxid generator. (As a matter of fact, some NO₂ is always formed, and will, depending upon the anolyte, form some nitric acid or nitrates within the cell, but the amount is small and does not detract materially from the action of the anode as a nitric oxid generator.)

It will be understood that, depending 75 upon conditions, a principal one being the amount of nitrogen supplied to the oxygen liberated (supposing a constant liberation of oxygen), nitric acid or its salts may, if desired, be produced within the cell instead of 80 merely (as above indicated) producing an anode gas containing a mixture of NO and

NO₂ in which the ratio $\frac{NO}{NO_2}$ is very large.

In any case, I prefer to supply nitrogen 85 somewhat in excess of the amount theoretically necessary for the particular reaction desired.

Illustrative of the above, the process may be performed to meet the conditions of several classes, say three, which three, for convenience, I designate "A," "B," and "C." These classes are characterized by:—A—the formation of nitric acid within the anode compartment of the cell, with acid electrolytes; B—the formation of nitrates within the anode compartment of the cell, with alkaline electrolytes; C—the formation of nitric oxid (NO) within the anode compartment of the cell for subsequent oxidation to 90 nitrogen peroxid (NO₂) by air and eventual conversion of the NO₂ to nitric acid or equivalent salts in the usual manner. I give an example in each of the classes. (In all cases, except Class A, where no attempt was made 95 to produce it, ammonia was formed at the cathode by the combination of electrolytic hydrogen with the nitrogen introduced at the cathode. Since it was not possible to determine accurately the internal surface 100 areas of the porous electrodes, the superficial areas were used for purposes of comparison 105 in recording current densities during the experiments) :—

Class A

115

In a cell constructed so that a porous anode of graphitized petroleum coke, with proper electrical contacts, was inclosed within an unglazed porcelain battery jar, 120 containing dilute nitric acid, and provided with means for forcing nitrogen through the anode, and the whole placed within a glass vessel containing dilute nitric acid, in which a rod of graphite was hung to act as 125 a cathode, the following typical results were obtained, the cell being operated at about room temperature (19 C.) and with a current density in both cases of about .054 ampere per square inch at the anode, that at 130

the cathode not being determined:—

HNO₃ in cell.

5	Electrolyte dilute HNO ₃ .	Volts.	Amp. hrs.	Before electroly- sis.	After electroly- sis.	HNO ₃ formed.	Current effi- ciency.
10	4.6% HNO ₃ .	3.18	45.1	Grams. 97.16 512.39	Grams. 108.82 516.46	Grams. 11.66 4.07	Per cent. 56 49.5
10	6.4% HNO ₃ .	3.5	18				

N. B.—Current efficiency calculated on the basis of nitrogen oxidation taking place to N₂O₅ electrolytically.

Class B.

15 In a cell similar to that used in Class A, except that the porous cathode was of graphitized petroleum coke contained in an unglazed porcelain battery jar with means for forcing nitrogen through it, the anode and cathode being submerged in the jars by 20 dilute sodium hydroxid solution, and surrounded by the same solution contained in a glass vessel, the following typical results were obtained, the cell being operated at 25 about room temperature, and with a current density in the first case of about .094 ampere per square inch at each electrode, and, in the second case, about .016 at the anode and .197 at the cathode:—

30	Electrolyte NaOH solution.	Volts.	Amp. hrs.	NaNO ₃ formed.	Current effi- ciency.	NH ₃ formed.
35	9.2%.....	3.3	63.79	Grams. 7.63	Per cent. 20	Amount not determin- ed.
35	9.5%.....	1.63	9.57	3.46	50	Do.

N. B.—Current efficiency calculated on same basis as in Class A.

Class C.

40 The cited experiments were carried out with a cell substantially like the illustrated and described cell (and it will be understood that such a cell may be used for "Class A" and "Class B" work).

45 The following table shows the effect on the anodic reactions of varying the current density, other conditions remaining constant:—

50	Anode gas.		NO NO ₂	Current density amps. per sq. in. superficial area of anode.
	NO ₂	NO		
55	Per cent. 7.1	Per cent. 61.42	8.65	0.033
	4.76	20.48	4.30	0.029
	21.16	26.09	1.08	0.073
	14.75	15.85	1.08	0.075
	12.08	12.08	1.00	0.066
60	18.75	18.75	1.00	0.068

Operating the cell with an anode current density of from 0.03 to 0.04 ampere per square inch of superficial area for 94 ampere hours, the nitric acid found in the absorption columns from the oxidation of the

NO produced at the anode was 60% of the theoretical amount possible.

The following summary of an experiment serves to illustrate the practical operation of the process for the production of nitric acid 70 and ammonia. In this case the temperature was about 19° C., about a 20% solution of sodium nitrate was used, and the current density at the anode was about .03—.04 ampere per sq. in., that at the cathode not 75 being determined.

Original electrolyte—sodium nitrate solution.

Anolyte contained 91.5 grams of nitrogen 80 as NaNO₃.

Catholyte contained 6.38 grams of nitrogen as NaNO₃.

Total in cell, 97.88 grams of nitrogen as 85 NaNO₃.

End of experiment—after 330 ampere hours.

Anolyte contained 6.01 grams of nitrogen as HNO₃.

Anolyte contained 91.50 grams of nitrogen 90 as NaNO₃.

Catholyte contained 6.69 grams of nitrogen as NH₃.

Absorption column #1 contained 23.65 95 gms. of nitrogen as HNO₃.

Absorption column #2 contained 6.89 gms. of nitrogen as HNO₃.

Ammonia absorber, contained 1.54 gms. of nitrogen as NH₃.

Grams of
nitrogen. 100

Total in cell and absorbers..... 135.78

Original amount..... 97.88

Gain by electrolysis..... 37.90

105

The 37.9 grams of nitrogen fixed were present as follows:—

From the anodic reaction 162.2 grams as HNO₃.

From the cathodic reaction 9.99 grams as 110 NH₃.

330 ampere hours should theoretically oxidize enough nitrogen to NO to produce 376.8 grams HNO₃. The anode actually produced 162.2 grams of HNO₃, hence the current efficiency was 43%.

At the cathode 330 ampere hours produced 9.99 grams of NH₃. Theoretically 63.19 grams of NH₃ should have been formed. The actual current efficiency at the 120 cathode was 15.8% of the theoretical. The ammonia yield in this particular case was low. Yields as high as 40% and 60%, and in one case 70%, of the theoretical have been obtained.

Owing to the secondary reactions that may take place in the region of the anode, it is impossible to describe definitely the exact phenomena of the nitrogen oxidation. There are several steps or stages of oxida- 130

tion, all possible under different conditions, and all producing nitric acid or its equivalent salt by reactions with the electrolyte, if complete oxidation occur in the cell, as:—

- 5 The oxidation may take place with the intermediate formation of nitric oxid (NO), the nitric oxid then taking on additional oxygen to form nitrogen peroxid (NO₂), and finally, by further successive oxidation, 10 nitrogen pentoxid (N₂O₅) may be formed. 10 nitrogen pentoxid (N₂O₅) may be formed. The latter reacts directly with water to form nitric acid:—

- 15 Or the nitrogen peroxid (NO₂) may first react with water to form a mixture of nitric acid and nitrous acid, thus:—

- 20 the nitrous acid then being further oxidized to nitric acid:—

- If the electrolyte be cold, reaction (2) would 25 probably take place; if the electrolyte be heated a little below the boiling point of water, the reaction would form nitric acid and nitric oxid, thus:—

- the nitric oxid split off from this reaction taking on additional oxygen to form nitrogen peroxid (NO₂) in which case the above reaction would be repeated. In whatever 35 manner the oxidation reactions take place, if complete oxidation to nitric acid takes place within the cell, it is necessary to liberate five molecular equivalents of oxygen for every two molecular equivalents of nitrogen oxidized.

I am aware that it is possible to find traces of nitrogen compounds in aqueous electrolytes, through which air or gases containing free nitrogen have been bubbled during electrolysis, in order to agitate the solution or to disengage electrolytic gas from the surface of the anode or cathode. And these traces of nitrogen compounds are without much question due to the direct chemical combination of the nitrogen dissolved in the solution and the oxygen and hydrogen liberated on the surface of the anode and cathode. But the fact that nitrogen is only very slightly soluble in water,—0.00295 gram in 100 cc. of water at 0° C. and less at higher temperatures,—makes the oxidation or hydrogenation of the dissolved nitrogen in aqueous electrolytes of no commercial significance.

- 60 It will be understood that the conditions of operating, and the particular cell used, may be changed in many ways without departing from the spirit of my invention. And it will also be understood, that many of 65 the principles and features of the invention

are broadly applicable to the performance of gas reactions other than the particular ones referred to by way of example, and therefore, so far as the principles of the invention are applicable to gas reactions 70 other than those having to do with nitrogen, I do not restrict the invention to processes involving nitrogen reactions. Also, references to "nitrogen gas", and so on, in the claims are not to be understood as restricting the invention to the use of isolated nitrogen, as the nitrogen may be supplied as the constituent of a mixture, as by passing air through the cell, the process then serving for the direct fixation of atmospheric nitrogen; the use of air being more particularly applicable to the oxidizing of the nitrogen at the anode. In performing the process conformable to the conditions of "Class C", with air, the electric current and the supply of air are so regulated that, so far as practicable, the supply of oxygen liberated by the cell is sufficient to oxidize the nitrogen to NO only.

In the carrying on of the process, after 90 the manner of Class A, or of Class B, where, as nearly as practicable, complete oxidation of the nitrogen takes place in the cell, it will be understood that the supply 95 of electric energy and the supply of nitrogen are preferably so relatively regulated that the oxygen liberated is sufficient to fully oxidize the nitrogen. When air is used rather than isolated nitrogen a reduction in the amount of oxygen liberated, can 100 be made, in consideration of the available oxygen in the air.

As previously indicated, the greater the porosity and the smaller the individual pores, the more nearly is the ideal condition approached in the subdivision of the body of the nitrogen gas. By the use of the graphitized petroleum coke electrodes, having, for pores, merely the minute pores in enormous number, characteristic of coke, 110 the desired condition of a great number of small pores, is arrived at conveniently. And so, too, with the fine steel wool suggested. But it will be understood that other materials, giving the desirable condition, 115 can be used without departing from the invention.

As will appear from the context, I have, in the foregoing description, generally used the term "electrolyte" in its newer sense 120 of "solution of a substance capable of being electrolyzed," but have, on occasion and for the sake of clearness, used it in its older sense to designate the substance itself. Also the terms "anolyte" and "catholyte" are 125 used to designate the solution in the anode and cathode compartments respectively.

When, as illustrated, each electrode is in substantially a single piece, they may include separable sub-structures as conical 130

plugs 25^a and 26^a, and 12^a, and the annulus 13^b, permitting the introduction of the thermometers, the tube 8 and the tube 13 with its ring-like part 13^a, such structures being forced into proper electrical contact with the major portions of the electrodes. The tubes 8 and 13 may be slid into place from below before the introduction of the electrodes into the containers, proper receiving spaces for the various tubes, and for the members 6, being provided in the electrodes as made, and the tube 8 and the members 6 being received in their respective electrodes in electrical contact therewith; the upper end of tube 13 being bent over, after the positioning of the tube and application of the ring 19. In an assembly such as that illustrated in Fig. 3, it will be understood that such pipe couplings and other fittings (not shown) as desired may be provided to facilitate convenient assembly.

I claim:—

1. The process of producing compounds by gas reactions and substantially independently of the solubility phenomena of the hereafter-named gaseous element relative to the hereafter-named fluid, which includes electrolyzing an electrolytic fluid containing an element liberatable as a gas and combinable with a gaseous second element, mechanically minutely dividing a body of said gaseous element, and mechanically, as distinguished from and substantially independent of working by virtue of the solubility of said gaseous element in said fluid, bringing the divisions of said body into intimate, direct contact with said first named element at the moment of its liberation from the fluid.

40 2. The process of producing compounds by gas reactions which includes electrolyzing, in a cell having a porous electrode, an electrolytic fluid containing an element liberatable as a gas at said electrode and combinable with a gaseous second element, and passing said second named element through the pores of said electrode during the electrolyzing, thereby to mechanically divide the body of gaseous second element into minute streams and mechanically bring said streams into contact with the liberatable element, and on and within the pores of the electrode, at the moment of its liberation.

55 3. The process of producing a nitrogen compound substantially independently of the solubility phenomena of nitrogen relative to the hereafter named fluid, which includes electrolyzing an electrolytic fluid containing an element liberatable as a gas and combinable with nitrogen, mechanically minutely dividing a body of nitrogen gas, and mechanically, as distinguished from and substantially independent of working by virtue of the solubility of nitrogen in said

fluid, bringing the divisions of said body into intimate direct contact with the liberated gas at the moment of its liberation.

4. The process of producing a nitrogen compound which includes electrolyzing, in 70 a cell having a porous electrode, an electrolytic fluid containing an element liberatable as a gas at said electrode and combinable with nitrogen, and passing nitrogen through the pores of said electrode during the electrolyzing, thereby to mechanically divide the body of nitrogen into minute streams and mechanically bring said streams into contact with the liberatable element, and on and within the pores of the electrode, at the 75 moment of its liberation.

5. The process of fixing nitrogen substantially independently of the solubility phenomena of nitrogen relative to water, which includes electrolyzing an aqueous electrolytic solution, mechanically minutely dividing a body of nitrogen gas, and mechanically, as distinguished from and substantially independent of working by virtue of the solubility of nitrogen in water, bringing 90 the divisions of said body into intimate, direct contact with gas liberated by the electrolysis, at the moment of its liberation.

6. The process of fixing nitrogen which includes electrolyzing an aqueous electrolytic solution in a cell having a porous electrode, and passing nitrogen gas through the pores of said electrode during the electrolysis, thereby to mechanically divide the body of nitrogen into minute streams and 100 mechanically bring said streams into contact with the gas liberated during electrolysis, and on and within the pores of the electrode, at the moment of its liberation.

7. The process of oxidizing nitrogen 105 which includes electrolyzing an electrolytic fluid containing oxygen, in a cell having a porous anode, and passing nitrogen gas through the pores of said anode during the electrolyzing, thereby to mechanically divide the body of nitrogen into minute streams and mechanically bring said streams into contact with the oxygen liberated during electrolysis, and on and within the pores of the anode, at the moment of its liberation.

8. The process of treating nitrogen to produce ammonia, which consists in electrolyzing an electrolytic fluid containing hydrogen, in a cell having a porous cathode, and passing nitrogen gas through the pores of said cathode during the electrolyzing, thereby to mechanically divide the body of nitrogen into minute streams and mechanically bring said streams into contact with the hydrogen liberated during electrolysis, 120 and on and within the pores of the cathode, at the moment of its liberation.

9. The process of producing a nitrogen compound substantially independently of the solubility phenomena of nitrogen rela- 130

tive to the hereafter named fluid, which consists in electrolyzing an electrolytic fluid containing an element liberatable as a gas and combinable with nitrogen, mechanically minutely dividing a body of nitrogen gas, and mechanically, as distinguished from and substantially independent of working by virtue of the solubility of nitrogen in said fluid, bringing the divisions of said body into intimate, direct contact with the liberated gas at the moment of its liberation, and causing the resulting product to react with a substance containing the element with which it is desired to fix the nitrogen to produce the desired compound.

10. The process of producing a nitrogen compound substantially independently of the solubility phenomena of nitrogen relative to the hereafter named fluid, which consists in electrolyzing an electrolytic fluid containing oxygen, mechanically minutely dividing a body of nitrogen and mechanically, as distinguished from and substantially independent of working by virtue of the solubility of nitrogen in said fluid, bringing the divisions of said body into intimate, direct contact with the liberated oxygen at the moment of its liberation, while so regulating the supply of electric energy and the supply of nitrogen that nitric oxid is formed, and removing said oxid from the cell and causing it to combine with the element with which it is desired to fix the nitrogen to produce the desired compound.

11. The process of producing a nitrogen compound substantially independently of the solubility phenomena of nitrogen relative to the hereafter-named fluid, which consists in electrolyzing an electrolytic fluid containing oxygen, mechanically minutely dividing a body of nitrogen and mechanically, as distinguished from and substantially independent of working by virtue of the solubility of nitrogen in said fluid, bringing the divisions of said body into intimate, direct contact with the liberated oxygen at the moment of its liberation, while so regulating the supply of electric energy and the supply of nitrogen as to provide, as nearly as practicable, for the oxidation of the nitrogen to nitric oxid only in the cell, and removing said oxid from the cell and causing it to combine with the element with which it is desired to fix the nitrogen to produce the desired compound.

12. The process of producing a nitrogen compound substantially independently of the solubility phenomena of nitrogen relative to the hereafter-named fluid which consists in electrolyzing an electrolytic fluid containing oxygen, said fluid also containing an element with which the nitrogen may be fixed, mechanically minutely dividing a body of nitrogen and mechani-

cally, as distinguished from and substantially independent of working by virtue of the solubility of nitrogen in said fluid, bringing the divisions of said body into intimate, direct contact with the liberated oxygen at the moment of its liberation, and permitting the resulting product to combine in the cell with the said fluid-contained element to fix the nitrogen.

13. In an electrolytic cell for the conducting of gas reactions, means for containing the electrolytic fluid, and electrodes therefor, one of said electrodes being porous to provide for the permeation thereof by gas.

14. In an electrolytic cell, means for containing the electrolytic fluid, electrodes therefor, one of said electrodes being porous, and means for conducting gas into such electrode and in communication with the pores thereof, thereby to provide for the introduction of gas into said pores to permeate such electrode.

15. In an electrolytic cell, means for containing the electrolytic fluid, electrodes therefor, one of said electrodes being porous, and means for conducting gas into such electrode, such means extending to adjacent the bottom of the electrode and being there in communication with the pores of such electrode thereby to provide for the introduction of gas into said pores to rise through such electrode.

16. In an electrolytic cell, means for containing the electrolytic fluid, electrodes therefor, one of said electrodes being porous, means for conducting gas into such electrode, means providing a gas chamber above such electrode, and means in communication with said chamber for conducting away gas.

17. In an electrolytic cell, means for containing the electrolytic fluid, electrodes therefor, one of said electrodes being porous and adapted to be submerged in the fluid, means for conducting gas into said electrode below the level of the fluid, and means above the level of the fluid and adjacent said electrode for conducting away the gaseous products from the electrode.

18. In an electrolytic cell, a container, means in the container dividing it into an anode compartment and a cathode compartment, an electrode for each compartment, one of said electrodes being porous and occupying the major portion of its compartment thereby to provide that the major portion of the liquid in such compartment shall lie within electrode pores, and means for conducting gas into the pores of the said porous electrode.

19. In an electrolytic cell, a container, means in the container dividing it into an anode compartment and a cathode compartment, an electrode for each compartment, one of said electrodes being porous and occupying the major portion of its compart-

ment thereby to provide that the major portion of the liquid in such compartment shall lie within electrode pores, means for conducting gas into the pores of the said 5 porous electrode, and means for conducting away the gaseous products from such electrode.

20. In an electrolytic cell, means for con-

taining the electrolytic fluid, electrodes therefor, one of said electrodes being porous, 10 and a member for conducting the current to such electrodes, said member being in the character of a tube providing a passage for gas.

In testimony whereof I affix my signature.
CHARLES B. JACOBS.
